PLATEN PRINTING PRESS

Lawrence R. Johnson, Cleveland, Ohio, assignor
to The Chandler & Price Company, Cleveland,
Ohio, a corporation of Ohio

Application April 11, 1934, Serial No. 720,083

10 Claims. (Cl. 101—408)

This invention relates as indicated to platen printing presses, but has reference more particularly to the platen grippers of such presses and to the means for controlling the movement of such grippers.

In printing presses of the Gordon or platen type, the platen is usually supported for oscillatory movement which must be imparted thereto in order to bring a sheet thereon in contact with the form. The platen is usually provided with two or more grippers which are mounted on a gripper bar that is pivotally attached at its respective ends to the lower edge of the platen. Incidentally to oscillation of the platen, the gripper bar is oscillated so as to swing the grippers carried thereby downwardly against the face of the platen, the function of the grippers being to retain the sheet in place during the printing operation. To accommodate the grippers to sheets of various sizes, they are preferably adjustably mounted on the gripper bar, being secured in desired location by means of suitable clamp nuts.

The platen oscillates between a substantially horizontal sheet-receiving position and a substantially vertical form-engaging or sheet-printing position, and the operation of the grippers which is synchronized with that of the platen has heretofore been so timed as to cause the grippers to recede from the face of the platen immediately after the return of the platen to its horizontal position has begun, so that shortly after the return movement has begun, the grippers are at their maximum angle of divergence with respect to the face of the platen. This early recession of the grippers from the platen has not been found to be particularly objectionable in presses operating at relatively low speeds or when printing on stock of substantial thickness.

I have found, however, in the operation of presses at high speeds, that the sheets were likely to be blown off the platen on the up-stroke of the latter, and that in working with very thin stock, that the sheets were likely to curl during the up-stroke of the platen, rendering the removal of the sheets therefrom extremely difficult.

The present invention accordingly has as its primary object the elimination of the aforesaid difficulties incidental to the operation of the platen presses. More specifically, it is the object of the invention to provide mechanism for delaying the opening or recessive movement of the grippers of platen presses during the up-stroke or return of the platen to sheet-receiving position. Another object of the invention is to

provide mechanism of the character set forth which may be driven by the press-operating mechanism. A further object of the invention is to provide mechanism of the character set forth which is independent of the platen or platen oscillating mechanism and which therefore may be adjusted without reference to the position of the platen or the platen actuating mechanism.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but a few of the various mechanical forms in which the principle of the invention may be utilized.

In said annexed drawings:—

Fig. 1 is a fragmentary elevation of the left side of a platen printing press embodying one form of the gripper-operating mechanism;

Fig. 2 is an enlarged view of the gripper-operating mechanism of Fig. 1, with the platen in substantially the form-contacting position;

Fig. 3 is a view similar to Fig. 2, but showing in dotted lines the position of the parts immediately preceding the arrival of the platen at the sheet-receiving position, and in solid lines, the position of the parts when the platen is in sheet-receiving position;

Figs. 4 and 5 are views of a modified form of mechanism for accomplishing the desired ends, the position of the platen in these figures corresponding with the positions of the platen in Figs. 2 and 3, respectively.

Referring more particularly to the drawings, there is shown in Fig. 1 a printing press of the Gordon or platen type, comprising a frame 1, upon which is oscillatably mounted the platen 2, oscillation of the platen being effected in the usual manner by the cam 3, which is mounted on the large driven gear 4 of the press. The gear 4 is disposed at the right side of the press and drives the gear 5 at the left side of the press, the gear 5 serving also as a head, by means of which the crankrod 6 is driven to oscillate the form (not shown) of the press. The gear 5 drives pinion 7, which in turn drives gear 8 mounted on the feeder cam shaft 9 of the press. Shaft 9 has mounted thereon a cam 10 which forms the actuating means for the mechanism now to be described.

The platen 2 has mounted thereon adjacent its lower edge brackets 11 which form a pivotal sup-

port for the gripper bar 12 upon which the grippers 13 are adjustably mounted. The bar 12 is provided with an integral lug or arm 14, the other end of which is pivotally secured to a link 15 having an elongated opening 16 in one end. Link 15 is connected to one arm 18 of a bell crank 17, as by means of a pin 19 extending through the opening 16. The pin 19 forms a pivotal connection between the bell crank and the link 15 which is normally maintained by means of a tension spring 20 which interconnects link 15 and arm 18. The opening 16, however, permits the grippers to be manually depressed when adjusting the same with reference to a sheet on the platen. The bell crank 17 is pivotally mounted on a shaft 21 supported by the throw-off lever bracket 22 mounted on the frame 1 of the press. The other arm 23 of the bell crank is provided at its lower end with a roller 24 which is always maintained in contact with the cam 10 as by means of a compression spring 25. One end of the spring 25 is in engagement with a fixed abutment 26 mounted on the frame of the press.

The operation of the aforesaid mechanism may be briefly described as follows: With the platen 2 in substantially the form-contacting position as shown in Fig. 2, the gripper 13 will be in engagement with the platen, that is, with the sheet on the platen. As the platen rises to the dotted-line position shown in Fig. 3, the grippers are maintained in engagement with the platen by virtue of the fact that the roller 24, due to the influence of springs 25, rides down the inclined portion 10a of the cam, thus forcing the link 15 to the left. When the platen is in the dotted-line position the roller 24 lies in the bottom 10b of the recess in the cam. During the movement of the platen from the dotted-line position to the solid line or sheet-receiving position, the bell crank 17 is suddenly moved in a clockwise direction by engagement of the shoulder 10c of the cam with the roller 24. This results in a sudden movement of the grippers 13 away from the platen, so as to permit removal of the printed sheet and the placing of the next sheet on the platen. On the down-stroke of the platen, the grippers remain at subsequently the same inclination, but the platen is gradually moved to a substantially vertical position so that when it is in the form-contacting position the grippers are again in engagement with the platen. It will be apparent from the foregoing description that the delay in the opening movement of the grippers will be effective to prevent the sheets from being blown off the platen on the up-stroke of the platen, and that thin sheets which would otherwise have a tendency to curl up will be prevented from curling.

In that form of the invention shown in Figs. 4 and 5, the gripper-operating mechanism is actuated by a cam 30 which is mounted on the inner surface of the small crank-rod driving head (not shown) of the press.

The gripper-operating mechanism in this case comprises a link 31 which corresponds with the link 15 in the previously described form of the invention except that it is not provided with an elongated opening at one end. Link 31 is pivotally connected with a lever 32 as by means of a pin 33, which forms a support for a roller 34, said roller being always maintained in contact with the cam 30 as by means of a compression spring 35. The lever 32 is pivotally mounted on the frame 1 of the press, as by means of a pin or stub shaft 36. The spring 35 permits the grippers 13

to be manually depressed when adjusting the same with respect to a sheet on the platen, thereby dispensing with the necessity for the elongated opening in link 31.

The operation of the aforesaid mechanism is as follows: With the platen 2 in substantially the form-contacting position as shown in Fig. 4, the grippers 13 will be in engagement with the sheet on the platen. As the platen rises to the dotted-line position shown in Fig. 5, the grippers are maintained in engagement with the platen by virtue of the fact that the roller 34, due to the influence of spring 35, rides up the inclined portion 30a of the cam, thus forcing the link 31 to the left. When the platen is in the dotted-line position, the roller 34 lies at the top 30b of the protuberance on the cam. During the movement of the platen from the dotted-line position to the solid line or sheet-receiving position the lever 32 is suddenly moved in a clockwise direction as the result of the roller 34 riding down the inclined portion 30c of the cam. This results in a sudden movement of the grippers 13 away from the platen, so as to permit removal of the printed sheets and the placing of the next sheet on the platen. On the down stroke of the platen, the grippers remain at substantially the same inclination, but the platen is gradually moved to its substantially vertical position, so that when it is in the form-contacting position, the grippers are again in engagement with the platen.

Instead of having the grippers open during the up-stroke of the platen, it is possible, by a slight variation of the contour or position of the cams 10 and 30, to delay the opening of the grippers until the platen has reached the end of its up-stroke or, in fact, to delay such opening until immediately after the platen has reached the end of its up-stroke. This may be desirable under certain conditions and is within the purview of the present invention.

It will be noted in each form of the invention that the gripper actuating mechanism is entirely independent of the oscillation of the platen or platen oscillating mechanism and that it may therefore be adjusted without reference to the position of the platen or the platen actuating mechanism. This is an important feature of the invention in that it enables the movements of the grippers to be controlled on both the up and down stroke of the platen in any desired manner.

Other modes of applying the principle of my invention may be employed instead of those explained, change being made as regards the mechanism herein disclosed, provided the means stated by any of the following claims or the equivalent of such stated means be employed.

I therefore particularly point out and distinctly claim as my invention:—

1. In a platen printing press, the combination of a platen, means for oscillating said platen between the sheet-receiving and printing position, grippers mounted for pivotal movement with respect to said platen and adapted to engage a sheet on the platen when the latter is in printing position, and means for maintaining said grippers in engagement with said sheet until the platen has returned to substantially the sheet-receiving position.

2. In a platen printing press, the combination of a platen oscillatable between a sheet-receiving and a printing position, grippers angularly movable with respect to said platen, and means for maintaining said grippers substantially parallel.

with the platen during the major portion of the movement of the platen from the printing to the sheet-receiving position.

3. In a platen printing press, the combination of a platen oscillatable between a sheet-receiving and a printing position, grippers angularly movable with respect to said platen, means for maintaining said grippers parallel with the platen during the major portion of the movement of the platen from the printing to the sheet-receiving position, and means for thereafter moving said grippers away from said platen.

4. In a platen printing press, the combination of a platen oscillatable between a sheet-receiving and a printing position, grippers mounted for pivotal movement towards and away from said platen, means for maintaining said grippers in contact with a sheet on said platen during movement of the platen from the printing to the sheet-receiving position, and means for suddenly moving said grippers away from said platen in the last stages of said movement.

5. In a platen printing press, the combination of a platen oscillatable between a sheet-receiving and a printing position, grippers mounted for pivotal movement toward and away from said platen, and cam and lever means for maintaining said grippers in contact with a sheet on said platen during the major portion of the movement of the platen from the printing to the sheet-receiving position.

6. In a platen printing press, the combination of a platen, means for oscillating said platen between the sheet-receiving and printing positions, grippers mounted for pivotal movement with respect to said platen and adapted to engage a sheet on the platen when the latter is in printing position, and means independent of the oscillation of the platen or platen oscillating means for maintaining said grippers in engagement with said sheet until the platen has returned to substantially the sheet-receiving position.

7. In a platen printing press, the combination of a platen oscillatable between a sheet-receiving and a printing position, grippers angularly movable with respect to said platen, and means independent of the oscillation of the platen for maintaining said grippers substantially parallel with the platen during the major portion of the

movement of the platen from the printing to the sheet-receiving position.

8. In a platen printing press, the combination of a platen, means for oscillating said platen between the sheet-receiving and printing position, grippers mounted for pivotal movement with respect to said platen and adapted to engage a sheet on the platen when the latter is in printing position, and means for maintaining said grippers in engagement with said sheet during the major portion of the movement of the platen from the printing to the sheet-receiving position and for thereafter moving said grippers away from said platen, said last-named means comprising a cam and a member pivotally mounted on the frame of said press and movable about its pivot by said cam.

9. In a platen printing press, the combination of a platen, means for oscillating said platen between the sheet-receiving and printing position, grippers mounted for pivotal movement with respect to said platen and adapted to engage a sheet on the platen when the latter is in printing position, and means for maintaining said grippers in engagement with said sheet during the major portion of the movement of the platen from the printing to the sheet-receiving position and for thereafter moving said grippers away from said platen, said last-named means comprising a cam, a member pivotally mounted on the frame of said press and a spring biasing said member towards said cam.

10. In a platen printing press, the combination of a platen, means for oscillating said platen between the sheet-receiving and printing position, grippers mounted for pivotal movement with respect to said platen and adapted to engage a sheet on the platen when the latter is in printing position, and means for maintaining said grippers in engagement with said sheet during the major portion of the movement of the platen from the printing to the sheet-receiving position and for thereafter moving said grippers away from said platen, said last-named means comprising a cam mounted on the shaft upon which the platen oscillating means is mounted, a member pivotally mounted on the frame of said press and a spring biasing said member towards said cam.

LAWRENCE R. JOHNSON.
